(57) **CLAIM**

The ornamental design for a strobe light animator toy, as shown and described.

DESCRIPTION

FIG. 1 is a top, front, and right perspective view of a strobe light animator toy;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the drawings are included for the purpose of illustrating portions of the strobe light animator toy that form no part of the claimed design.
